UNITED STATES PATENT OFFICE.

CASPER SCHAEFER, OF CAMBRIDGE CITY, INDIANA.

COMBINATION HEATER AND RADIATOR.

No. 863,318.

Specification of Letters Patent.

Patented Aug. 13, 1907.

Application filed November 22, 1906. Serial No. 344,538.

To all whom it may concern:

Be it known that I, CASPER SCHAEFER, a citizen of the United States, residing at Cambridge City, in the county of Wayne and State of Indiana, have invented 5 certain new and useful Improvements in Combination Heaters and Radiators; and I do declare the following to be a full, clear, and exact description of the invention, reference being had to the accompanying drawings, and to the letters and figures of reference marked 10 theron, which form a part of this specification.

This invention relates to apparatus of the class that may be used either as a gas heater or as a stove pipe radiator, the invention having reference particularly to heat radiators that are adapted for heating dwellings.

15 Objects of the invention are to provide improved highly efficient radiators at moderate expense and which may be durable and economical in use, another object being to provide means whereby radiators of the above-mentioned character may be readily cleaned 20 and kept free from soot conveniently in order to obtain the best results with the least amount of heat, a still further object being to provide a gas heater which may be adapted to be readily connected to a stove pipe to be used as a radiator.

25 With the above-mentioned and minor objects in view, the invention consists in an improved radiator provided with a detachable gas burner and adapted to be connected to a stove pipe, the radiator having adjustable and movable connected baffle plates therein 30 serving as scrapers, and having also a movable scraper for cleaning the interior of the shell of the radiator; and the invention consists further in the novel parts and the combinations and arrangements of parts as hereinafter particularly described and pointed out in 35 the appended claims.

Referring to the drawings, Figure 1 is a side elevation of the heating apparatus provided with a gas burner and connected to a stove pipe, the shell being partially broken away to expose internal parts; Fig. 2, a top 40 plan of the radiator disconnected from the stove pipe; Fig. 3, a vertical central sectional view with the supporting legs and gas burner omitted; Fig. 4, a horizontal sectional view on the line A A in Fig. 1; Fig. 5, a side elevation showing the baffle plates and their connector which serves as a heat deflector and the handles for the operation and adjustment thereof; Fig. 6, a top 45 plan of one of the two baffle plates employed as seen looking down at the line B B in Fig. 3; Fig. 7, a perspective view of the shell scraper; and, Fig. 8, a fragmentary perspective view of a portion of the shell scraper.

Similar reference characters in the various figures of the drawings designate corresponding elements or features of construction.

55 In a practical embodiment of the invention a design-

nates a base plate, and a' a top plate of the radiator which have circular openings b and b' respectively, arranged in circles, the plates being circular in plan and connected to opposite ends of a tubular shell c. A suitable number of heating tubes d are connected to the said plates at the openings b and b' therein for the passage of air to be heated. The base plate a is provided with a suitable number of supporting legs e and has a central annular flange f extending about an inlet opening and adapted to be connected to a stove pipe. 60 The top plate a' is provided with an annular flange f' to which a stove pipe g may be connected for conducting smoke or fumes from the interior of the radiator. The collars f and f' have less diameter than the circle of heating tubes. A suitable burner holder h is detachably connected to the flange f by means of bolts h', and a gas burner i having an inlet pipe i' is supported by the holder so as to be central below the base plate a opposite the inlet opening therein. Suitable rods j extend from the plate a to the plate a' and secure them 65 to the shell and the tubes.

Two baffle plates k and k' each have a suitable number of circular openings l to receive the heating tubes d, and the baffle plates may slide over the tubes, the plates preferably having scalloped edges l'. A tube 80 m extends between the two baffle plates k and k' and is secured thereto holding the baffle plates at a suitable predetermined distance apart so that all may be moved together. The baffle plates have openings n and n' 85 therein through which extend handle rods o and o' which are secured to the baffle plates by means of fasteners p which may be formed as U-bolts or staples. The handle rods are provided with stop pins q inserted in pin holes r so that the baffle plates may be supported adjustably by permitting the pins to rest upon the top 90 plate a'.

In order to scrape the inner side of the shell c to remove soot therefrom, an annular scraper s is arranged within the shell and extends about the group of heating tubes d and is provided with handle rods t and t' of sufficient length to extend entirely through the top plate a' when the scraper is down, at or near the base plate a, so that the scraper may be moved throughout the whole length of the casing. The scraper and the handle rods are preferably made of two pieces of wire, each 100 piece being bent to form a half part of the scraper and attached to the opposite handle rod by being twisted about it as at u, although obviously the scraper may be otherwise constructed.

In practical use the radiator should be placed upon 105 a floor over a stove pipe hole therein, and the stove pipe extended through the floor and connected to the flange f by swinging the holder h out of the way and shifting the position of the burner i so as to clear the stove pipe, or in case the heating-stove may not be in 110

use, the stove pipe may be readily disconnected from the flange *f* and then the gas burner may be quickly placed in proper position as indicated in Fig. 1, so that the room may be heated conveniently by means of the 5 gas burner.

In case of accumulations of soot on the inner side of the shell *c* and on the exterior of the tubes *d*, the surfaces may be readily scraped by means of the scraper *s* and the baffle plates *k* and *k'* serving as scrapers as 10 above indicated, which will be found of great advantage in obtaining the highest degree of radiation of the heat, it being understood that the hot gases and the smoke, if any, will be deflected by the plate *k* so as to pass upwardly around the plate and will be deflected 15 by the connector *m* towards the heating tubes *d* between the plates *k* and *k'*, and then deflected by the plate *k'* around the edge thereof, the gases then passing out of the radiator through the pipe *g*. The soot will drop down onto the plate *a*, but with a strong draft 20 much of it will pass out through the pipe *g* and the chimney flue, but in case of an accumulation on the base plate *a*, it may remain without serious detriment, and in such case it may be desirable to readjust the plates *k* and *k'* so as to elevate them somewhat, and 25 while the plate *a* may be entirely free from soot, the baffle plates may be lowered so as to deflect the heat to the shell and tubes near the bottom of the radiator.

Ordinarily there will be no occasion for disconnecting the stove pipe from the radiator for removing the soot 30 during a whole winter season, and not at all if the scraping devices are frequently used so that unusual deposits will be avoided, it being understood that the scrapers will break up or pulverize the soot, so that it may readily pass out with strong draft.

35 Having thus described the invention, what is claimed as new is—

1. A radiator comprising a shell, a circular group of heating tubes, a pair of end plates connected to the shell and the tubes, a pair of baffle-plates movable on the tubes, 40 a tubular connector within the circular group of tubes at-

tached to the baffle-plates and movable therewith, and a pair of handle-rods connected to one of the baffle-plates.

2. A radiator comprising a shell, heating tubes, a pair of end plates connected to the shell and the tubes, and an adjustable deflector comprising a pair of baffle-plates and 45 a tubular connector guided by the tubes, the connector being attached to the baffle-plates, and the baffle-plates having openings to receive the tubes.

3. A radiator comprising a shell, heating tubes, end-plates connected to the shell and the tubes, a pair of baffle-plates movable on the tubes and having a tubular connector attached thereto serving to deflect currents towards 50 the tubes, and means for moving and adjusting the baffle-plates and the deflecting connector with respect to the end plates.

4. A radiator comprising a shell, a group of heating tubes, end-plates connected to the shell and the tubes, a pair of baffle-plates movable on the tubes, a tubular connector attached to the baffle-plates spacing them apart and 55 movable therewith, handle-rods connected to one of the baffle-plates, a scraper adjacent to the shell and movable about the group of tubes and past the baffle-plates and connector, and a handle-rod connected to the scraper.

5. A combination heater and radiator comprising a base-plate with an inlet opening therein, a shell and a circular group of heating-tubes connected to the base-plate, an aperture top-plate connected to the shell and the tubes, supporting legs attached to the base-plate, a burner-holder connected adjustably to the base-plate, a gas burner mounted removably on the burner-holder, a pair of baffle- 65 plates movable on the tubes, a tubular connector attached to the baffle-plates and movable therewith, and a pair of handle-rods connected to one of the baffle-plates.

6. The combination with a radiator having a shell and a circular group of heating tubes, and end plates connected 75 with the shell and the tubes, of a pair of baffle-plates spaced apart on the tubes, a tubular connector within the circular group of tubes and attached to the baffle-plates, and a pair of handle-rods attached to one of the pair of baffle- 80 plates and provided with stops to coöperate with one of the end-plates to gage and hold the baffle-plates relatively to the end-plates.

In testimony whereof, I affix my signature in presence of two witnesses.

CASPER SCHAEFER.
